UNITED STATES PATENT OFFICE.

HENRY J. GAISMAN, OF NEW YORK, N. Y.

HUMIDOR.

Application filed July 11, 1922. Serial No. 574,326.

To all whom it may concern:

Be it known that I, HENRY J. GAISMAN, a citizen of the United States, and resident of the borough of Manhattan, New York city, in the county of New York and State of New York, have invented certain new and useful Improvements in Humidors, of which the following is a specification.

My invention relates to improvements in humidors, and is particularly adapted for use in cigar boxes and the like to keep the tobacco moistened.

In carrying out my invention I provide a container for water and an absorbent adapted to be sustained in a cigar box or the like and to receive water from the container, means to maintain said absorbent in operative position and means to detachably sustain the container and the absorbent in operative relation within a cigar box or the like.

My invention also comprises novel details of improvement that will be more fully set forth and then pointed out in the claims.

Reference is to be had to the accompanying drawings forming part hereof, wherein

Fig. 1 is a plan view illustrating my improved humidor in position in a cigar box;

Fig. 2 is a cross section on line 2, 2 in Fig. 1;

Fig. 3 is a plan view of my improved humidor;

Fig. 4 is an end view of Fig. 3;

Fig. 5 is a detail section on line 5, 5, in Fig. 3; and

Fig. 6 is a detail perspective view.

Similar numerals of reference indicate corresponding parts in the several views.

At 1 is indicated a container for water, which may be of any suitable construction, shown provided at one end with a neck 2 receiving a stopper 3 which may be of suitable absorbent material, such as felt, to which may be attached a suitable wick 4 located within the container to supply the stopper with water by capillary action. At 5 is a strip of absorbent material, such as blotting paper, maintained in contact with stopper 3. The absorbent strip 5 is shown located in a retainer 6 shown comprising a member having spaced walls 6^a, 6^b formed by folding a strip of metal, as in U-form, having the upper side open for insertion and removal of absorbent strip 5. One wall, 6^b, is provided with perforations

7 to permit moisture to pass from the absorbent in the retainer. The retainer is also shown provided with an opening 6^c against which the stopper 3 is maintained in use to supply water to the absorbent strip 5. The wall 6^b of the retainer, surrounding the opening 6^c, is shown provided with a projecting rib or neck 8 adapted to receive the neck 2 of container 1 to retain the latter in operative position with respect to the container 6 and the absorbent 5. The retainer 6 is shown provided with laterally extending lugs 6^d to rest on a support, such as the wall of a cigar box. An arm or brace 9 extends from the retainer 6 at an angle thereto, and is provided with means to co-operate with container 1 to retain the latter in operative relation to absorbent strip 5. I have shown the arm or brace 9 provided with a support 10 having a tube 11 extending outwardly from said support and closed at its outer end, said tube opening through the inner side of said brace. Within tube 11 is a coiled spring 12 normally tending to push a plunger 13 against container 1. Said container is shown provided with a seat 14 at the end opposite stopper 3 to retain plunger 13. The container may be applied by placing its seat 14 against plunger 13 and pushing the same against the action of spring 12 so that the stopper 3 and neck 2 of the container may be inserted in the rib or neck 8 of retainer 6, whereby spring 12 will push plunger 13 against the container and thus the latter will be supported between said plunger and the retainer. The container may be removed for re-filling by pushing it against plunger 13 to release the container from rib 8.

I provide adjustable means to retain the humidor in a cigar box or the like for ready insertion and removal. For such purpose I have shown a slid able member 15 carried by arm or brace 9, which member is shown provided with guiding means 16, shown comprising the marginal edges of said member bent inwardly forming guiding grooves at 16^a that receive the marginal edges 9^a of arm or brace 9, (Fig. 5). The arm or brace 9 is shown provided with a slot 9^b receiving a lug 15^a projecting from member 15, adapted to engage the material at the outer end of slot 9^b to limit the outward movement of member 15 on arm or brace 9. A spring 17 shown guided by tube 11 and bear-

ing against brace 10 and against an out-turned or laterally disposed stop 15^b on member 15 tends normally to press said member outwardly. The stop 15^b is shown provided with a projection 18 in the form of a sharp point or pin, adapted to engage the wall of a cigar box or the like to retain the humidor.

The arm or brace 9 may be permanently united with retainer 6 or may be detachable therefrom. In Figs. 1 to 5, I have illustrated the arm 9 as secured permanently to the wall 6^b of retainer 6, which may be done by means of solder, the adjacent end of arm 10 9 being turned laterally at 9^c and provided with a hole 9^d, said arm carrying the rib 8 around said hole, whereby the hole 9^d opposes the hole 6^c in wall 6^b of retainer 6.

In Fig. 6 the wall 6^b of retainer 6 is shown provided with a projection 19, the marginal edges of which are bent over at 19^a to receive the marginal edges 9^a of arm or brace 9, whereby the parts 19 and 9 are slidably united. By means of this construction the 20 retainer 6 may be detached from the arm or brace 9 for convenience in packing and storing, as for shipment of the humidor, and said parts may be attached together when the humidor is to be used.

When my improvements are to be used the parts are assembled as shown in Figs. 1 and 2, with container 1 between retainer 6 and plunger 13, so that the stopper 3 will engage the absorbent material 5, the container having been charged with water. The absorbent material 5 will be maintained moist by contact with the wet stopper 3 and the wick 4, will supply said stopper with water in various positions of the humidor. The 30 humidor may be placed transversely in a cigar box A with the wall 6^a of retainer 6 resting against a wall of the box and the lugs 6^d resting upon the upper edge of the box wall, with the projection or pin 18 bearing against the opposite box wall, whereby the humidor will be suspended within the box by reason of the pressure of spring 17 which tends to push member 15 outwardly. In accordance with the distance between the 40 opposing box walls the member 15 will be adjusted along the arm or brace 9 to accommodate the boxes of different widths. The entire humidor may be readily placed within and removed from the box, and while the humidor is in position in the box the container 1 may be removed, recharged and replaced without requiring the entire device to be removed from the box, since the plunger is movable independently of arm or brace 9.

While I have referred to my improved humidor as adapted to be used within cigar boxes, it will be understood that the same may be used in any desired relations where moisture is to be maintained either in con-

nection with tobacco or for other purposes.

Changes may be made in the detail of construction set forth, within the scope of the appended claims, without departing from the spirit of my invention.

Having now described my invention, what I claim is:

1. A humidor comprising a container, an absorbent material, means to support the absorbent material along a box wall, and means to maintain the container in operative relation to the absorbent material between the box walls.

2. A humidor comprising a container having an absorbent stopper, a piece of absorbent material to cooperate with said stopper, a retainer for said absorbent material, means to support the retainer along a box wall, and means to maintain the container in cooperation with the absorbent material between the box walls.

3. A humidor comprising a container having an absorbent stopper, a piece of absorbent material to cooperate with said stopper, a retainer for said absorbent material, means to support the retainer along a box wall, a spring co-operative with the container to maintain its stopper in co-operation with the absorbent material, and means connected with the retainer and co-operative with said spring to maintain the container and the retainer between said walls.

4. A humidor comprising a container having an absorbent stopper, a piece of absorbent material to co-operate with said stopper, a retainer for said absorbent material, a plunger to engage the container, a spring normally forcing the plunger toward the container, and an arm extending from the retainer and co-operative with said spring.

5. A humidor comprising a retainer having perforations, absorbent material carried by the retainer, said retainer having an arm, a container having an absorbent stopper to co-operate with the absorbent material, and resilient means carried by said arm to retain the container in co-operation with the retainer.

6. A humidor comprising a retainer having perforations, absorbent material carried by the retainer, said retainer having an arm, a container having an absorbent stopper to co-operate with the absorbent material, a plunger movably carried by the arm to co-operate with the container, and a spring normally pushing the plunger toward the container.

7. A humidor comprising a retainer having perforations, absorbent material carried by the retainer, an arm extending from the retainer, a member movably connected with said arm, a spring normally tending to move said member outwardly along the arm, a container having means to supply fluid to said absorbent material, and means to de-

tachably retain the container in co-operation with said absorbent material.

8. A humidor comprising a retainer having perforations, absorbent material carried by the retainer, an arm extending from the retainer, a member movably connected with said arm, a spring normally tending to move said member outwardly along the arm, said member having a point to engage a box wall, 10 a container having means to co-operate with the absorbent material, and resilient means connected with said arm to normally retain the container in co-operation with the resilient material.
- 15 9. A humidor comprising a retainer having perforations and having a rib around an opening in the retainer, an arm connected with the retainer, a member slidably guided by the arm, said arm having a support, said 20 member having a projection spaced from the support, a spring interposed between said support and projection to normally move the member outwardly, a container having means to co-operate with the absorb- 25 ent material, and means to detachably retain the container between said support and retainer.
10. A humidor comprising a retainer having perforations and having a rib around an opening in the retainer, an arm connected with the retainer, a member slidably guided by the arm, said arm having a support, said 30 member having a projection spaced from

the support, a spring interposed between said support and projection to normally move the member outwardly, said support having a tube, a plunger and a spring operative in said tube, and a container adapted to engage said plunger to be retained between the retainer and the plunger. 35

11. A humidor comprising a retainer having spaced walls to receive an absorbent material therebetween, one of said walls having one or more laterally disposed lugs, one of said walls having perforations and a hole, 40 a rib surrounding said hole, an arm connected with said retainer, a container having a neck adapted to be retained by said rib, and means upon said arm to maintain said neck in co-operation with said rib. 50

12. A humidor comprising a retainer having spaced walls to receive an absorbent material therebetween, one of said walls having one or more laterally disposed lugs, one of said walls having perforations 55 and a hole, a rib surrounding said hole, an arm connected with said retainer, a container having a neck adapted to be retained by said rib, means upon said arm to maintain said neck in co-operation 60 with said rib, a member slidably connected with said arm and a spring co-operative between said arm and member for forcing the latter outwardly.

HENRY J. GAISMAN.
